[57] CLAIM

The ornamental design for a surgical table top, as shown and described.

DESCRIPTION

FIG. 1 is a perspective view of a surgical table top, showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing in FIGS. 1-7 is for illustrative purposes only and forms no part of the claimed design.
